CLAIM

The ornamental design for a display screen or portion thereof with computer icon, as shown and described.

DESCRIPTION

FIG. 1 is a view of a first image in a sequence of a display screen or portion thereof with computer icon in accordance with a first embodiment of our new design;

FIG. 2 is a view of a second image in a sequence of a display screen or portion thereof with computer icon in accordance with the first embodiment of our new design;

FIG. 3 is a view of a first image in a sequence of a display screen or portion thereof with computer icon in accordance with a second embodiment of our new design;

FIG. 4 is a view of a second image in a sequence of a display screen or portion thereof with computer icon in accordance with the second embodiment of our new design; and,

FIG. 5 is a view of a third image in a sequence a display screen or portion thereof with computer icon in accordance with the second embodiment of our new design.

The subject matter in FIGS. 1 through 2 of this patent application includes a process or period in which an image changes into another image. This process or period forms no part of the claimed design. The subject matter in FIGS. 3 through 5 of this patent application also includes a process or period in which an image changes into another image. This process or period forms no part of the claimed design. The outermost broken lines illustrate a display screen or a portion thereof and form no part of the claimed design.
